ABSTRACT

Hydrocarbyl phosphorus acids, preferably hydrocarbyl orthophosphoric acids and hydrocarbyl pyrophosphoric acids are converted to the corresponding phosphoramidates by direct reaction with urea. The phosphoramidates, alone or with a hydrocarbyl phosphorus acid, are useful as additives in petroleum hydrocarbon compositions to which they impart such desirable properties as corrosion resistance.

1

PROCESS FOR THE FORMATION OF PHOSPHORAMIDATES

BACKGROUND OF THE INVENTION

Amido derivatives of hydrocarbyl phosphorous acids find utility in a number of applications such as additives in petroleum hydrocarbon compositions and as functional fluids, e.g., hydraulic fluids, coolants, damping fluids, etc. Preferred are amido derivatives of hydrocarbyl orthophosphoric acids.

For example, heretofore amido derivatives of hydrocarbyl orthophosphoric acids have been prepared by reacting ammonia or an amine with a hydrocarbyl orthophosphoryl chloride. A typical example of the prior art process is the reaction of ammonia with diethyl orthophosphoryl chloride:

One readily apparent deficiency of the above prior art process is that low overall yields of the orthophosphoramidate are obtained because the usual procedure requires preparation of diethyl orthophosphoryl chloride in low yield by reaction of ethanol with phosphoryl chloride. In addition, the orthophosphoramidate product must be separated from the by-products of acidic ammonium chloride and traces of corrosive hydrogen chloride. There is thus an added expense inherent in the use of the prior art process.

SUMMARY

It is an object of this invention to provide a novel process for the conversion of hydrocarbyl phosphorus acids to the corresponding phosphoramidates.

It is another object of this invention to provide an economical process for the conversion of hydrocarbyl phosphorus acids to the corresponding phosphoramidates which does not involve the formation of corrosive by-products.

It is a particular object of this invention to provide a novel process for the conversion of hydrocarbyl orthophosphoric acids and hydrocarbyl pyrophosphoric acids to the corresponding hydrocarbyl phosphoramidates.

Other objects will be apparent to those skilled in the art from the disclosure contained herein.

The foregoing objects are attained according to the process of this invention. Broadly, this invention consists of a process for the conversion of hydrocarbyl phosphorus acids to the corresponding hydrocarbyl phosphoramidates comprising reacting urea with a hydrocarbyl phosphorus acid selected from the group consisting of hydrocarbyl orthophosphoric acids and hydrocarbyl pyrophosphoric acids.

By proceeding according to the process of this invention, it is possible to readily and economically convert a hydrocarbyl phosphorus acid to the corresponding hydrocarbyl phosphoramidate. The process is characterized by the absence of by-product hydrogen halide or ammonium halide.

DESCRIPTION OF THE PREFERRED EMBODIMENTS

This invention is concerned with a novel process for the conversion of hydrocarbyl phosphorus acids to the

corresponding hydrocarbyl phosphoramidates. Broadly, the process involves the reaction of the hydrocarbyl phosphorus acid with urea to form the hydrocarbyl phosphoramidate. The process is characterized by the absence of corrosive by-products. The process requires that the hydrocarbyl phosphorus acid have at least one OH group bonded to phosphorus. The reaction occurring in the process of the instant invention is typified by the reaction of diethyl orthophosphoric acid 10 with urea.

The process of this invention is especially useful in the conversion of hydrocarbyl orthophosphoric acids and hydrocarbyl pyrophosphoric acids to the corresponding hydrocarbyl phosphoramidates. It is essential that the hydrocarbyl phosphorus acid have at least one OH group bonded to phosphorus. Thus, in the case of hydrocarbyl orthophosphoric acids, either monohydrocarbyl orthophosphoric acid or dihydrocarbyl orthophosphoric acid may be converted to the corresponding hydrocarbyl phosphoramidates. By the same token, hydrocarbyl pyrophosphoric acids useful in the practice of this invention may be monohydrocarbyl, dihydrocarbyl, or trihydrocarbyl pyrophosphoric acids. In the case where the hydrocarbyl phosphorus acid contains more than one OH group bonded to phosphorus, all or part of the OH groups may be replaced by NH₂ groups. However, it appears most likely that only one OH group bonded to any one phosphorus is easily replaced by NH₂ since the first OH group appears to be more reactive than the second. Thus, for example, a monohydrocarbyl pyrophosphoric acid is preferably converted to the monohydrocarbyl pyrophosphoramidate.

In the above equation, R represents a hydrocarbyl group.

The hydrocarbyl groups of the hydrocarbyl phosphorus acids may be aliphatic, aromatic, naphthenic, or may contain various mixtures of aliphatic, aromatic, and naphthenic portions. Aliphatic and naphthenic groups may be either saturated or unsaturated. In addition, the hydrocarbyl groups in any one hydrocarbyl phosphorus acid containing more than one hydrocarbyl group may be either the same or different. While the choice of hydrocarbyl groups in the hydrocarbyl phosphorus acids is not critical, alkyl groups are preferred. Most preferred are branched chain alkyl groups. The size of the hydrocarbyl groups is not critical. However, the hydrocarbyl groups generally contain about 1 to 55 carbons, and preferably about 5 to 35 carbons. Especially preferred are hydrocarbyl groups containing

about 8 to 20 carbons. Following are examples of hydrocarbyl phosphorus acids that may be converted to hydrocarbyl phosphoramides by the process of this invention.

Dimethyl orthophosphoric acid
 Mono-p-tolyl orthophosphoric acid
 Di(2-ethylhexyl) orthophosphoric acid
 Cyclohexyl eicosyl orthophosphoric acid
 Monoisooctyl orthophosphoric acid
 Diisooctyl orthophosphoric acid
 Diphenyl orthophosphoric acid
 Monoctadecyl orthophosphoric acid
 Heptyl triacontyl orthophosphoric acid
 Tripropyl pyrophosphoric acid
 2-Ethylhexyl isooctyl pyrophosphoric acid
 Phenyl pyrophosphoric acid
 p-Tolyl nonyl pyrophosphoric acid
 Tricyclohexyl pyrophosphoric acid
 Undecyl eicosyl pyrophosphoric acid
 Dimethyl pyrophosphoric acid

If desired, various mixtures of the above hydrocarbyl phosphorus acids may be used. It will be understood that the foregoing hydrocarbyl phosphorus acids are merely illustrative and applicant does not restrict his invention thereto. However the preferred hydrocarbyl phosphorus acids are hydrocarbyl orthophosphoric acids, particularly di(2-ethylhexyl) orthophosphoric acid and mixtures of monoisooctyl orthophosphoric acid and diisooctyl orthophosphoric acid.

The amount of urea to be reacted with the hydrocarbyl phosphorus acid will generally be about 1 mole of urea for each equivalent of OH groups of the hydrocarbyl phosphorus acid that is to be converted to NH₂ groups. Thus, 1 mole of a dihydrocarbyl orthophosphoric acid will be reacted with about 1 mole of urea. Similarly, 1 mole of a monohydrocarbyl orthophosphoric acid can be reacted with about 2 moles of urea if the desired product is the monohydrocarbyl orthophosphordiamide or with about 1 mole of urea if the desired product is the monohydrocarbyl acid orthophosphoramidate. It is apparent that from the stoichiometry of the process as disclosed herein, one skilled in the art will be able to determine the ratio of urea to hydrocarbyl phosphorus acid to obtain the desired product.

The process of the instant invention is usually carried out in an inert solvent in which the reactants are soluble or may be rendered soluble as by heating, but choice of solvents is not critical and is well within the capability of one skilled in the art to make. However, it has been found that toluene is generally a preferred solvent.

The choice of the reaction temperature employed in the process of this invention is empirical. Generally, a temperature sufficiently high to cause solution of the reactants is the minimum employed. Reaction temperatures within the range of about 100°-200°C., and preferably about 110°-155°C., are usually employed.

The course of the reaction is readily followed by the evolution of ammonia. The reaction is generally complete when evolution of ammonia ceases. Thus, the reaction time will vary depending on such factors as the reactivity of the OH group in the phosphorus acid and the reaction temperature, i.e., the higher the temperature, the shorter the reaction time as a rule. Thus, the reaction time will vary depending on the reactivity of the OH group and on reaction conditions. The opti-

mum reaction time will be within the ability of one skilled in the art to determine, based on these factors.

This invention will be further illustrated by the following specific examples.

EXAMPLE I

In a round bottom flask fitted with a stirrer and reflux condenser are placed 200 ml. of reagent grade toluene, 161.0 g. (0.500 mole) of di(2-ethylhexyl) orthophosphoric acid, and 30.0 g. (0.500 mole) of reagent grade urea. The stirred reaction mixture is then heated under reflux. The urea, which is initially insoluble in the cold toluene, goes into solution as the reflux temperature is approached. After about one-half hour of stirring the reaction mixture under reflux, evolution of ammonia is detected. The mixture is stirred under reflux for a total of 9 hours at which point the evolution of ammonia has ceased. The reaction mixture, which contains a white precipitate believed to be decomposition products of urea such as biuret and cyanuric acid, is filtered. The filtrate is distilled under a reduced pressure of 17 mm. of Hg to leave a clear, tan, oily liquid residue weighing 161.7 g. as the reaction product. Infrared spectroscopy of the product as evidenced by absorption bands in the region 3,500-3,000 cm.⁻¹, indicates N-H stretching of the P-NH₂ group. In addition, elemental analysis of 2.74 percent nitrogen by the Kjeldahl method indicates the reaction product to be a mixture of about 2 parts di(2-ethylhexyl) orthophosphoramidate and about 1 part unreacted di(2-ethylhexyl) orthophosphoric acid.

EXAMPLE II

Example I is substantially repeated using 200 ml. of reagent grade toluene, a quantity of an approximately equimolar mixture of mono- and diisooctyl orthophosphoric acids sufficient to contain 1.08 equivalents of OH groups, and 1 mole of reagent grade urea. The stirred reaction mixture is heated under reflux. The initially insoluble urea dissolves when the pot temperature reaches about 113° C. The reaction mixture is stirred under reflux for a total of about 17.6 hours during which time the pot temperature varies from about 115° C. to a peak of about 190° C. Apart from a period of about 1 hour when the pot temperature reaches a peak of about 190° C., the pot temperature is maintained within the range of about 115°-153° C. Evolution of ammonia is first detected after about one-half hour of refluxing. Ammonia is still being evolved at the end of the approximately 17.6 hour reflux period when the reaction is stopped.

The reaction mixture is then filtered to remove a white precipitate believed to be decomposition products of urea such as biuret and cyanuric acid. The filtrate is distilled under reduced pressure leaving a clear, viscous liquid weighing 160.8 g. as the reaction product. Elemental analysis shows the reaction product to contain 2.37 percent nitrogen as determined by the Kjeldahl method. An infrared spectrum of the product has bands in the region 3,500-3,000 cm.⁻¹

While the instant invention has been illustrated by certain specific examples, it will be appreciated by those skilled in the art that the process of the invention is broadly operable on hydrocarbyl orthophosphoric acids and hydrocarbyl pyrophosphoric acids. The primary requirement is that the hydrocarbyl phosphorus acid contain at least one OH group bonded to phosphorus.

Hydrocarbyl orthophosphoramidates are known as additives for use in petroleum hydrocarbon products. For example, they are used in leaded gasoline compositions for the purpose of reducing surface ignition and spark plug fouling. I have found that mixtures of hydrocarbyl orthophosphoramidates and the unreacted hydrocarbyl orthophosphoric acid precursor, when incorporated in petroleum hydrocarbon products, impart thereto excellent anti-corrosion properties. Mixtures of hydrocarbyl orthophosphoramidates and unreacted hydrocarbyl orthophosphoric acids in the desired proportions may be obtained by the process of this invention. The degree of conversion of the hydrocarbyl orthophosphoric acid to the hydrocarbyl orthophosphoramidate is readily controlled by varying the amount of urea and proper choice of reaction parameters such as temperature and reaction time.

It will be understood that the specific embodiments set forth herein are illustrative only and the invention is not to be limited except as set forth in the following claims.

I claim:

1. A process for the conversion of a hydrocarbyl phosphorus acid to the corresponding hydrocarbyl phosphoramidate by conversion of OH groups bonded to the phosphorus of said acid to NH₂ groups comprising reacting at a temperature within the range of about

100°-200° C 1 mole of urea per equivalent of said OH groups to be converted to NH₂ wherein said hydrocarbyl phosphorus acid is selected from the group consisting of hydrocarbyl orthophosphoric acid and hydrocarbyl pyrophosphoric acid and wherein each hydrocarbyl group of said acid contains about 1 to 55 carbons.

2. The process of claim 1 wherein the hydrocarbyl phosphorus acid is a hydrocarbyl orthophosphoric acid in which the hydrocarbyl groups are alkyl groups.

3. The process of claim 2 wherein the alkyl groups are branched.

4. The process of claim 3 wherein the branched alkyl groups contain about 5 to 35 carbons.

5. The process of claim 4 wherein the reaction is carried out at a temperature in the range of about 110°-155° C.

6. The process of claim 5 wherein the reaction is carried out in toluene as the solvent.

7. The process of claim 6 wherein the hydrocarbyl orthophosphoric acid is di(2-ethylhexyl) orthophosphoric acid.

8. The process of claim 6 wherein the hydrocarbyl orthophosphoric acid is a mixture of monoisoctyl orthophosphoric acid and diisoctyl orthophosphoric acid.
